REELING DEVICE

Neil V. Smith, Los Angeles, Calif.

Application May 10, 1946, Serial No. 668,908

13 Claims. (Cl. 242—86)

1

This invention has to do with a reeling device and is more particularly concerned with a device suitable for handling a hose, or the like. It is a general object of the present invention to provide a reeling device suitable for handling hose, or the like, which is simple and inexpensive of manufacture, which is compact, and which will handle a hose, or like element, in a convenient and most advantageous manner.

It is an object of this invention to provide a compact power unit for handling long lengths of hose or the like, which power unit acts to wind the hose onto the reel with the desired amount of pull and without a whipping action occurring as the last few turns of hose are wound onto the reel. The action that I provide is an improvement over that obtained in mechanisms composed of weights and springs, or the like, or mechanisms driven by motors which require cumbersome gear trains, racks or other expensive devices.

There are numerous situations where electric cables, hoses, or like elements are normally carried on a reel and when in use they are withdrawn from the reel to later be allowed to wind back onto the reel under the influence of power applied to the reel. An example of such a situation is to be found in most gasoline service stations where air and water hoses are carried on reels and are rapidly withdrawn for use, and when their use is finished they are released so that they wind back automatically. A practical difficulty or disadvantage of the usual hose reel mechanism is that it winds the hose in so that the outer end portion of the hose is traveling at a substantial speed as it reaches its final retracted position, making it necessary to be stopped suddenly, which exerts unnecessary strain upon it and, more important, causing it to whip or lash in a disagreeable and often disadvantageous manner.

It is a general object of the present invention to provide a reeling device that will handle a hose so that the hose is effectively wound onto the reel upon being released and yet is checked in its final movement so that it comes to rest gently and without lashing or excessive strains, such as I have referred to above.

Another object of the invention is to provide an improved mechanism for handling a hose reel in which mechanism there is a hydraulic or pneumatic means incorporated so that it effectively exerts a desirable resistance to withdrawal of the hose and is operable to reel up or return

2

the hose in a most advantageous and effective manner.

The various objects and features of my invention will be fully understood from the following detailed description of a typical preferred form and application of the invention, throughout which description reference is made to the accompanying drawings, in which:

Fig. 1 is a side view of the reeling device that I have provided, showing the reel proper in cross section. Fig. 2 is a sectional view of the apparatus taken substantially as indicated by line 2—2 on Fig. 1, showing the reel proper removed from the balance of the machine. Fig. 3 is an enlarged detailed sectional view taken substantially as indicated by line 3—3 on Fig. 2. Fig. 4 is an enlarged view of the valve included in the hydraulic or pneumatic means employed in the apparatus. Fig. 5 is an enlarged plan view taken substantially as indicated by line 5—5 on Fig. 2 and showing the pulley incorporated in the device to handle the driving line. Fig. 6 is a view taken as indicated by line 6—6 on Fig. 5. Fig. 7 is a sectional view taken as indicated by line 7—7 on Fig. 5, and Figs. 8 and 9 are views illustrating the operating relationship of the driving line, the drum that handles the driving line, and the pulley over which the driving line operates; Fig. 8 showing the position of the parts when the apparatus is operated so that the hose is in, and Fig. 9 showing the relationship of the parts when the hose is out.

The apparatus that I have provided can be used to advantage in handling various objects such, for example, as electrical cables, hoses, and the like. However, since it is particularly advantageous for use in handling an air hose or the like, I have shown it in a form suitable for handling a hose H and I will refer to it as handling a hose, it being understood that when I use the term hose I mean to include any other or like element that may be handled like a hose.

The structure that I have provided involves, generally, a reel A that handles the hose H, a driving drum B for the reel, a flexible member or driving line C carried by and operating the drum B, a pulley D over which a loop portion X of the driving line is arranged, a cross head E, mounting means F supporting the pulley on or from the cross head, and a single means G controlling action of the cross head and serving to move the cross head to cause operation of the reel to wind in the hose H.

The reel A may be a simple or plain reel shaped and proportioned to properly accommodate the

hose H being handled by the apparatus. In the drawings I have shown a reel A characterized by a hub 10 with radially projecting flanges 11 at the ends of the hub. In the particular construction shown in the drawings the flange at the inner end of the reel projects radially inward to have a mounting flange 12 by which the reel is secured to the drum B, as shown in Fig. 3 of the drawings.

When the reel A is employed to carry a hose, or the like, means is provided for supplying a suitable fluid to the hose. In the case illustrated the supply means for the hose involves a fixed central fitting 13 mounted as hereinafter described to be concentric with the reel A, a delivery pipe having a section 14 entering the fitting 13, and a section 15 connected to the hose H, and packing means 16 establishing a fluid tight connection between the fitting 13 and pipe section 14.

The driving drum B is a differential drum on which are wound the end portions of a length of cable or the like. The cable which I refer to as a drive line C has both ends secured to the driving drum and is related to the driving drum so that its two end portions wind onto the drum in opposite directions. Further, the drive line is related to or carried by the driving drum so that it has the loop portion X which in the arrangement illustrated depends from or is below the drum where it extends around the pulley D. The driving drum B is made to have a differential action by forming it so that it has two end sections 20 and 21 of different sizes or diameters, the end section 20 being considerably smaller in diameter than the section 21. The two sections of the drum are preferably concentric with each other and are joined together end to end, as shown in Fig. 3. In practice the cable carrying surfaces or peripheries of the drum sections may be plain or they may, as I have shown in the drawings, be grooved to aid in guiding the drive line as it wraps onto the drum. Furthermore, the two sections 20 and 21 of the driving drum may be varied considerably in form or shape. For instance, they may be straight cylindrical drum parts or they may be varied in diameter at different points along their lengths. In the particular case illustrated both drum sections are shown somewhat tapered and they are related so that the large end of the small section 20 is innermost while the large end of the large section 21 is outermost.

A feature of the present invention is the formation of the drum at the inner or adjoining ends of the sections so that the cable carrying parts of the two drum sections are equal in size or substantially equal in size where the drum sections adjoin. It is to be understood that I may vary or even reverse the pulling action, or the relative sizes of the cable carrying parts to break or counteract the overtravel that might otherwise result from the action of inertia. In the particular form of the invention illustrated I gain substantial equality in size between the inner or adjoining ends of the drum sections by providing the large drum section 21 with a steeply tapered inner end portion 22 which corresponds in diameter with the inner end of the drum section 20 where the two drum sections are joined. Through this formation of the large drum section the last few turns of the drive cable around the drum section 21 decrease in size as they approach the inner end of the small drum section so that the innermost or last turn of the line on the large drum section is of the same diameter as the innermost turn at the inner end of the small section of the drum. It will be observed that since the drive

line is wound in opposite directions onto the two drum sections, and since the drum sections are of equal or substantially equal diameter where their inner ends adjoin, the structure operates so that the loop X of the drive line does not change in length or size when the drive drum is rotating and the end portions of the drive line are both at or adjacent the point at which the drum sections join, as shown in Fig. 8. When the end sections of the drive line are at or near the outer ends of the two drum sections, as shown in Fig. 9, there is a maximum change in the size of the loop X for a given amount of movement or rotation of the drive drum, this being due to the fact that under this condition as shown in Fig. 9, one end of the line is on a rather small diameter at the outer end of the drum section 20 while the other end of the line is on a large diameter at the outer end of the large drum section 21.

The drive drum B that I have hereinabove described may, in practice, be mounted in any suitable manner although I prefer to mount it immediately adjacent and concentric to the reel A as shown throughout the drawings. In the case illustrated in the drawings the flange part 12 of the reel A is secured directly to the outer or foremost end of the small drum section 20 by bolts 24 or other suitable fastening means, so that the reel A and drum B form a rigid or continuous unit. In the preferred construction the drum B has a central hub 25 rotatably mounted on a spindle 26 projecting from a frame element 27. In the case illustrated the spindle 26 is a hollow or tubular spindle which is in effect integral with the frame element 27 and the fitting 13 hereinabove referred to is threaded or otherwise attached to the end of the spindle on which the drum B is rotatably mounted. The reel A may have a central hub portion 25' secured to the flange part 11 of the reel by bolts 24', and the hub 25' may be rotatably mounted in a bearing 26' carried by a frame element 27'. The frame elements 27 and 27' are shown as integral parts of the frame structure 50 as will be seen in Fig. 1 of the drawings.

The cross head E carries the pulley D and serves as a connecting link between the drive line C and the means G. In the arrangement illustrated the cross head E is located below the drive drum B and the drive cable loops down from the drum B to extend around the pulley D carried by the cross head. The bearing or mounting means F supports the pulley D on or from the cross head E so that the pulley revolves about an axis located in a horizontal plane and is bodily rotatable within limits about a vertical axis. The cross head E moves bodily in a vertical direction and it is maintained so that it extends in a substantially horizontal direction transverse of the axis of the driving drum B. The cross head has a central or intermediate neck portion 30 which serves to offset the two side portions 31 of the head in the manner clearly shown in Fig. 5 of the drawings.

The bearing or mounting means F that I have shown in the drawings involves, generally, a split bearing block 33 that surrounds the neck portion 30 of the cross head and has its sections assembled so that it is supported for limited rotation on the ends of a vertically disposed pivot pin 34 carried by the neck 30 of the cross head. A ring 35 surrounds the sections of the bearing block 33 and a retainer plate 36 is secured to a radially projecting flange portion 37 of the bearing block so that the several parts just referred

to are held in the desired assembled position as shown in Fig. 7 of the drawings. The retainer plate 36 is an annular part releasably held in place by suitable fastening means such as bolts 38.

The pulley D is rotatably supported on or carried by the bearing structure just described, it being preferred to rotatably support it on the ring 35 so that it is retained in position by the flange 37 and retainer plate 36. With the pulley thus mounted it is freely rotatable on an axis lying in a horizontal plane and it is limitably rotatable about the vertical axis of the pivot pin 34. It is desirable to have the pulley freely rotatable about a horizontal axis as it serves to carry the loop of the drive line as the apparatus operates and it is desirable that the pulley be limitably rotatable on a vertical axis from a position such as is shown in full lines in Fig. 5 to one shown in dotted lines in Fig. 5, so that the line leads onto and from the pulley with a minimum of drag or friction. It will be understood from an examination of Figs. 8 and 9 how the pulley rotates as the apparatus operates between the two positions there illustrated.

The means G may vary widely in form and construction. In the particular form of the invention illustrated the means G is a hydraulic or pneumatic means and it serves to yieldingly resist operation of the apparatus that allows withdrawal of the hose H and it acts to drive or operate the apparatus so that the reel A is driven to wind the hose into the apparatus. In the particular case illustrated the means G involves one or more hydraulic units 40 and a control valve 41. In the case illustrated I show two hydraulic units 40, one connected to each end of the cross head E, and I show a single control valve 41 connecting the units with a pressure supply line 42 conducting operating fluid to the apparatus.

Each of the hydraulic units 40, as shown in the drawings, involves a vertically disposed cylinder 43 closed at its ends by heads 44 and 45. A piston 46 operates in the cylinder and a piston rod 47 connects to the piston and extends down through the cylinder head 45 to connect to one end of the cross head E, as clearly shown throughout the drawings. The units 40 are mounted on or carried by the frame structure 50 of the apparatus so that they are rigid and permanently located and thus serve to maintain the cross head E in the desired position beneath the drive drum B. The control valve 41 includes, generally, a body 60 having a main opening 61 and two branch openings 62. The branch openings 62 are connected to the upper ends of the cylinders 43 by suitable pipe connections 63. The main opening 61 of the body is connected with the fluid supply pipe 42 which may, where the device is handling an air hose H, be the air line which supplies air to the cylinders 43.

The body of the valve is provided with a seat 65 at the main opening 61 and a valve head 66 with a stem 67 cooperates with the seat 65. There is a central longitudinal bleed passage 68 through the combined valve head 66 and stem 67 and a plurality of spaced lugs 69 project from the head in a cage 70 that occurs at the outer end portion of the opening 61. The action of the valve is such that when the head 66 is lifted from the seat 65 the main opening 61 is open allowing fluid to flow freely through the control valve in a manner to allow fluid to escape from the valve or from the hydraulic units through the valve into the supply line 42 against the resistance of

fluid in the supply line. This occurs as the hose is being withdrawn and the power or strain applied to the hose turns the reel A and consequently the drum B in a manner to work the drive line C so that the cross head E is moved to operate the pistons 46 upward in the cylinders 43 displacing fluid from the upper ends of the cylinders and causing it to be forced out through the control valve 41. By nature of this device the volumetric displacement of the cylinders is very small for a large number of revolutions of the drum, and therefore only small quantities of fluid must be forced into the supply line. When the hose is released the fluid pressure from supply line 42 acts to close the valve so the head 66 seats on the seat 65 and there is a limited flow of fluid through the bleed opening 68 through the valve and into the hydraulic units forcing the pistons 46 down. As the pistons 46 move down they move the cross head E down and that acts on the loop of the drive line causing the drum B to be rotated in a manner to wind the hose H onto the reel A. By properly relating the size of the bleed opening 68 to the other parts of the apparatus and to the fluid pressure available the desired rate of speed of winding of the hose onto the reel is obtained.

Through the construction that I have described it will be apparent that the head of fluid existing in the supply line 42 will create a substantially constant pressure on the pistons 46 in the cylinders 43 and this pressure or force is transmitted through the piston rods and cross head to the pulley D and through the pulley and drive line it acts to rotate the differential drum B. Due to the differences and variations in diameters of the sections 20 and 21 of the drum causing them to have different turning moments where the line passes onto and off of them the constant pressure exerted by the means G through the drive line C is converted by differential action into rotative force which operates the reel so that when the apparatus has been operated to the point where the hose is all but completely wound onto the reel A, the speed of rotation of the reel A is checked or decreased and when the hose is finally wound completely in, the driving of the drum has been stopped or completely checked, due to the fact that the two ends of the drive line are depending from opposite sides of the drum and from parts of the drum of equal diameter thus creating a turning moment of zero as hereinabove described.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. In an apparatus of the character described, a reel, a drive line, a differential drum having aligned line carrying portions of different diameters and driving the reel, the line having its end portions wound in opposite directions on said portions of the drum, and means applying force to the line to rotate the drum the largest of said drum portions having a reduced end of substantially the same diameter as the smallest of said drum portions.

2. In an apparatus of the character described, a reel, a drive line, a differential drum in direct driving engagement with the reel and having adjoining portions of different diameters, the line

having its end portions wound in opposite directions on said portions of the drum, and means applying force to the line to rotate the drum the inner end of the largest portion of the drum having a reduced part of substantially the same diameter as the smallest portion of the drum.

3. In apparatus of the character described, a reel, a drive line, a drum driving the reel and having portions of different diameters tapered in the same direction, the end parts of the line being wound in opposite directions on said portions of the drum, and means applying force to the line to rotate the drum the small end of the largest portion of the drum being of substantially the same diameter as the large end of the smallest portion of the drum.

4. In apparatus of the character described, a reel, a drive line, a drum driving the reel and having portions of different diameters with parts of the line wound on them in opposite directions, and means applying force to the line to rotate the drum, one part of the drum being tapered and having a line carrying portion of substantially the same diameter as the other part of the drum.

5. In apparatus of the character described, a reel, a drive line, a drum having end portions of different diameters and arranged end to end, one portion having a tapered section at its inner end having a line carrying part substantially the same in diameter as the other portion of the drum, the line having one end attached to the outer end of one drum portion and having an end attached to the inner end of the other drum portion, the ends of the line being wound in opposite directions on the two portions of the drum, and means operating the line to turn the drum.

6. In apparatus of the character described, a reel, a drive line, a drum driving the reel and having portions of different diameters arranged end to end with parts of the line wound on it in opposite directions, and means applying force to the line to rotate the drum, the line being attached to the outer end of the smallest drum portion and to the inner end of the largest drum portion.

7. In apparatus of the character described, a reel, a drive line, a drum having end portions of different diameters and arranged end to end, one portion having a tapered section at its inner end having a line carrying part substantially the same in diameter as the other portion of the drum, the line having one end attached to the outer end of one drum portion and having an end attached to the inner end of the other drum portion, the ends of the line being wound in opposite directions on the two portions of the drum leaving the center portion of the line in the form of a loop, and means operating the line to turn the drum including a pulley engaging the looped center portion of the line and means shifting the pulley causing the line to turn the drum.

8. In apparatus of the character described, a reel, a drive line, a differential drum having portions of different diameters and driving the reel, the line having portions wound in opposite directions on said portions of the drum, and means applying force to the line to rotate the drum including, a power driven member guided to reciprocate, a pulley engaging the line, and bearing means carried by said member to reciprocate therewith and tiltably and rotatably supporting the pulley.

9. In apparatus of the character described, a reel, a drive line, a differential drum having

portions of different diameters and driving the reel, the line having portions wound in opposite directions on said portions of the drum, and means applying force to the line to rotate the drum including a power driven reciprocating cross head, and a pulley engaging the line and tiltably and rotatably supported by the cross head.

10. In apparatus of the character described, a reel, a drive line, a differential drum having portions of different diameters and driving the reel, the line having portions wound in opposite directions on said portions of the drum, and means applying force to the line to rotate the drum including a cross head, a pulley engaging the line and tiltably and rotatably supported by the cross head, and fluid pressure actuated means supporting and reciprocating the cross head.

11. In apparatus of the character described, a reel, a drive line, a differential drum having portions of different diameters and driving the reel, the line having portions wound in opposite directions on said portions of the drum, and means applying force to the line to rotate the drum including a cross head, a pulley engaging the line and tiltably and rotatably supported by the cross head, and fluid pressure actuated means carrying and operating the cross head and including a control valve establishing free flow in one direction and restricted flow in the other direction.

12. In apparatus of the character described, a reel, a drive line, a differential drum having portions of different diameters and driving the reel, the line having portions wound in opposite directions on said portions of the drum, and means applying force to the line to rotate the drum including a cross head, a pulley engaging the line and tiltably and rotatably supported by the cross head, and fluid pressure actuated means carrying and operating the cross head and including a cylinder and piston unit and a control valve for the unit establishing free flow in one direction and restricted flow in the other direction.

13. In apparatus of the character described, a reel, a drive line, a differential drum having portions of different diameters and driving the reel, the line having portions wound in opposite directions on said portions of the drum, and means applying force to the line to rotate the drum including a cylinder and piston unit laterally offset from the drum for moving the line and a control valve for said unit establishing free flow from the unit and restricted flow to the unit.
